CHAIR AND LIKE SEATING**Robert Bailey, London, England, assignor to J. Cinnamon Limited, London, England**

Filed June 3, 1959, Ser. No. 817,867

Claims priority, application Great Britain June 5, 1958 10

3 Claims. (Cl. 155—179)

This invention relates to resilient seatings for easy 15 chairs, settees or vehicles (hereinafter referred to as chairs), of the type wholly or mainly employing tension springs.

This kind of tension spring seating where loose cushioning is employed has the disadvantages that the tension spring arrangement in time becomes impressed on the underside of the overlying cushion, and may be such as to make the cushion unsuitable for reversal, and that the tension spring arrangement requires a substantial and thick upholstery or loose cushion (usually of foam rubber) which is expensive.

An aim of the present invention is to provide a seating structure which will avoid these disadvantages by eliminating the liability of the said spring impressions and by providing for the use of a thinner or less expensive overlying cushion.

The invention consists in a resilient seating structure comprising an upper deck of canvas or other flexible material of an outline congruent with the shape of the chair framing in the region of the seating plane, supported at the edges on tension springs arranged more or less parallel with the seat framing and anchored to said framing; a lower deck of canvas or other flexible material spaced vertically from and preferably of substantially less area than the upper deck to afford resilient support mainly in the buttocks area and supported by tension springs radiating or extending outwardly therefrom to said chair framing; and a relatively thin resilient cushion of an area substantially confined to that of the buttocks, secured sandwichwise between the two decks.

In carrying the invention into effect various embodiments of the resilient seating will be hereinafter described with reference to the accompanying drawings in which:

Figure 1 is an isometric view of a chair having one form of resilient seating embodying the features of the invention.

Figure 2 is a side elevation of the chair shown in Figure 1.

Figure 3 is a plan view taken on line 3—3 of Figure 2 showing the arrangement of the springs supporting the upper deck of the seating.

Figure 4 is a plan view taken on line 4—4 of Figure 2 showing the arrangement of the springs supporting the lower deck of the seating with the intermediary cushion removed.

Figures 5 to 9 are partial plan views of various modified forms of the seating showing various alternative arrangements of the springs supporting the lower deck.

Figure 10 is a partial plan view of a further modified form of the seating showing an alternative arrangement of the lower deck and the springs supporting the same.

With regard to the embodiment of the invention shown in Figures 1 to 4 the resilient seating of the chair 1 is formed by two spaced decks of canvas or other flexible but inextensible material disposed one above the other to form an upper deck 2 and a lower deck 3. Each deck

2

is independently supported within the area defined by the chair framing structure in the region of the seating plane and formed by side members 4 by tension springs 5 and 6 anchored to brackets 7 secured to the chair at or adjacent the corners of said framing structure. The brackets each have a pair of spaced arms or lugs 7a and 7b adapted for receiving, or attachment to, the ends of the deck supporting springs and each bracket is secured to the framing structure with one of the lugs thereon located above the other so that the uppermost lug 7a of each bracket lies substantially in the plane of the upper deck 2 and the lower lug 7b lies substantially in the plane of the lower deck 3.

The area and outline of the upper deck 2 is generally congruent with the shape of the chair frame structure in the region of the seating plane and a tubular pocket or seam 8 is provided at each of the four marginal edges of the deck each to receive a tension spring 5 forming part of the resilient support for the upper deck. Each spring 5 extends through its respective pocket 8 generally parallel and closely adjacent to a side 4 of the seat frame structure and its ends are anchored to the uppermost lugs 7a of two of the corner brackets 7.

The upper deck 2 is thus supported at the edges by 25 four tension springs 5 and the tension in these springs is such as to exert a pull on the upper deck tending to tighten and stretch the same across the area defined by the seat framing structure in the seating plane. The lower deck 3 is spaced vertically from, but is preferably of smaller area than, the upper deck 2 to afford resilient support mainly in the buttocks area and is supported by tension springs 6 radiating from the corners thereof to the corner brackets 7 on the chair frame structure in the region of the seating plane.

The lower deck 3 is preferably of quadrilateral or rectangular form generally similar in outline to that of the upper deck 2 and the four corners thereof are each turned or folded over and secured to provide an oblique tubular pocket or loop 9 at each corner of the deck. A rod or bar 10 is passed through and located within each pocket 9 with the ends of the rod or bar protruding slightly beyond the ends of the pocket. A pair of tension springs 6 are each attached at one end to one of the protruding ends of each bar 10, and the other ends of the springs are anchored to the lower lug 7b of a bracket 7 secured to the adjacent corner of the frame structure. The rods 10 spread or space apart the ends of the springs 6 attached thereto so that each pair of springs converges outwardly of the lower deck towards the adjacent corner bracket 7 and assumes a generally V formation. The tension in the springs 6 retain the lower deck 3 stretched taut in a plane below and substantially parallel to that of the upper deck 2. The resilient seating is completed by a relatively thin resilient cushion 11 which is located sandwichwise between the two decks 2 and 3. The cushion 11 may be of foamed rubber, plastic or any suitable resilient padding material, and is preferably enclosed within a cover or envelope which may be secured, detachably or otherwise, to one or both of the decks to retain the cushion in position. Alternatively, the cushion 11 may consist of an envelope enclosing a series of short compression springs arranged in any known manner.

If desired, a further relatively thin cushion (not shown) may be provided for overlying the upper deck 2.

It is to be understood that methods and means other than hereinbefore described may be employed for attaching the tension springs to the edges or corners of the upper and lower decks respectively. Eyelets, for example, may be provided in the edges or corners of the decks to receive the ends of the springs.

Modified or alternative arrangements of springs to that described above may be provided for supporting the

lower deck 3 such as shown in Figures 5 to 9. As shown in Figure 5, each corner of the lower deck 3 has an oblique tubular pocket 9 with a spreader bar 10 passing therethrough with the ends thereof protruding therebeyond in a similar manner to that described above with regard to Figures 1 to 4. A pair of tension springs 6, each attached at one end to one of the protruding ends of the bar 10 extend outwardly parallel to each other to the adjacent corner of the chair framing and are anchored at their outer ends on the lower lug 7b of the bracket 7.

In the arrangement shown in Figure 6 each corner of the lower deck 3 is provided with an eyelet 12 and a pair of tension springs 6, disposed coaxially one within the other, are secured at one end to said eyelet 12 and extend outwardly to the adjacent corner of chair frame, the outer ends of the springs 6 being anchored to the lower lug 7b of the bracket 7 in the corner of the frame. With regard to the arrangement shown in Figure 7 a pair of tension springs 7 are secured at one end to an eyelet 12 provided in each corner of the lower deck 3 and extend outwardly to the adjacent corner of chair frame. The outer ends of the springs 6 are anchored to the lower lug 7b of the bracket 7 in the corner of the frame in spaced relationship so that the springs assume a V formation and diverge outwardly of said corner of the deck 3.

In the arrangement shown in Figure 8 a single tension spring 6 is secured at one end to an eyelet 12 in each corner of the lower deck 3 and anchored at its outer end to the lug 7b of the bracket 7 in the adjacent corner of the chair frame.

The arrangement of the tension springs 6 shown in Figure 9 is generally similar to that described hereinbefore in respect of Figures 1 to 4 for supporting the lower deck 3, but, in addition to the springs 6, further tension springs 13 are provided, each extending from an eyelet 12 located on each edge of the lower deck 3 intermediate the corners thereof to a suitable bracket or lug 14 located on each side frame member 4 intermediate the corners of the frame structure. Alternatively, any of the spring arrangements shown in Figures 5 to 8 may be substituted for that shown in Figure 9. Further, it is contemplated that more than one tension spring 13 may be located between each edge of the deck 3 and adjacent side frame member 4.

The upper deck as applied to a quadrilateral seat framing and referred to hereinbefore, will have its edges parallel to said framing with the lower deck similarly orientated. It will be appreciated that with a modified system or arrangement of springing the lower deck could be disposed diamondwise with respect to the quadrilateral chair frame structure in the region of the seating plane. An example of this arrangement is shown in Figure 10 wherein the outer ends of springs 6 arranged as described hereinbefore with reference to Figures 1 to 4, instead of being anchored to bottom lugs of brackets 7 are anchored to brackets 14 located on the side frame members 4 intermediate the corners of the frame structure. Alternatively, any of the arrangements of the corner springs 6 shown in Figures 5 to 8 may be substituted for supporting the lower deck diamondwise with respect to the quadrilateral chair frame structure.

Where the invention is applied to chairs or the like with seat framings other than quadrilateral, i.e. tub chairs, it will be understood that the upper deck will have an outline conforming to the particular configuration of such seat framing. In these latter circumstances, the lower deck may be shaped similarly to the upper deck or it may be quadrilateral.

The resilient seating may be applied to a chair having any known form of back support, resilient or otherwise, or such seating may equally well be applied to a chair in combination with a resilient back support formed by spaced flexible decks supported by tension springs with a cushion sandwiched therebetween in a manner similar to that described hereinbefore with regard to the seating.

I claim:

1. A resilient seating structure for a chair comprising an upper deck of canvas or other flexible material of an outline congruent with the shape of the chair framing in the region of the seating plane, supported at the edges on tension springs arranged more or less parallel with the seat framing and anchored to said framing; a lower deck of canvas or other flexible material spaced vertically from and preferably of substantially less area than the upper deck to afford resilient support mainly in the buttocks area and supported by tension springs radiating or extending outwardly therefrom to said chair framing and a relatively thin resilient cushion of an area substantially confined to that of the buttocks, secured sandwichwise between the two decks.

2. A resilient seating structure as claimed in claim 1 wherein the chair framing in the region of the seating plane is of quadrilateral form, both decks are disposed within the confines of said chair framing in the region of the seating plane with their edges parallel to the sides thereof, the tension springs supporting the edges of the upper deck are anchored at the corners of said chair framing and the tension springs supporting the lower deck radiate from the corners thereof towards the adjacent corners of the chair framing to which they are anchored.

3. A resilient seating structure for a chair having seat framing of quadrilateral form comprising, a resilient cushion interposed between two vertically spaced decks of canvas or like flexible material, each resiliently supported independently of the other within the confines of the seat framing, the uppermost deck having a quadrilateral outline corresponding to the shape of the seat framing and being supported at its edges by tension springs anchored to the corners of the seat framing to extend parallel to the sides of said framing, and the lower deck having a quadrilateral outline and being supported in diamondwise relation to the seat framing beneath the uppermost deck by tension springs secured to its corners and radiating outwardly therefrom to anchorage points on the sides of the seat framing intermediate the corners of said framing.
